Primary Examiner — Cynthia R Underwood

(74) Attorney, Agent, or Firm — True Shepherd LLC;
Andrew C. Cheng(57) **CLAIM**

The ornamental design for magnet hook, as shown and described.

DESCRIPTION

FIG. 1 is a perspective view of a magnet hook showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the magnet hook and form no part of the claimed design.

1 Claim, 8 Drawing Sheets(56)
